UNITED STATES PATENT OFFICE.

HORATIO G. GILLMOR, OF WASHINGTON, DISTRICT OF COLUMBIA.

RAIL ANCHOR.

Application filed October 4, 1922. Serial No. 592,322.

My invention relates to devices known as rail anchors, rail stays or anticreepers and one of its objects is to form a simple device which will prevent the longitudinal movement of the rails of railways.

Other objects are to provide a device which comprises but one piece and may be made from round or rectangular rolled bars without wasting material. Other objects are to provide a device which, while of ample strength to withstand all the stresses to which it is subjected in service, shall be light in weight; to provide a device which may be readily applied with the tools usually employed by track mechanics; and to provide for locking the device upon the rail in such manner as to prevent the accidental loosening or detachment of the device.

In the accompanying drawings, in which one embodiment of the invention is illustrated:

Figure 1 is an elevation showing the rail in section.

Figure 2 is an elevation of the rail, showing a portion of the tie in section and a portion of the rail in side elevation.

Figure 3 is a bottom view, looking up with two positions of the device shown in dotted lines to illustrate the manner in which the device is applied to the rail.

Figure 4 is a perspective view of the device.

Similar letters refer to similar parts throughout the several views.

A represents the rail, B the cross tie and C the rail anchor.

The rail anchor C comprises a rolled bar one end B of which is bent over to form a jaw adapted to grip the base of the rail A at one side of the rail. Upon the other end of the rail anchor C there is formed a portion E, which when the rail anchor C is in position on the rail extends above the plane of the bottom of the rail and provides a surface F adapted to engage the edge of the base of the rail A. The bar, of which the rail anchor C is constructed is bent downwardly from the portion E and then upwardly to form a portion G adapted to engage the face of the tie B and the end of the bar is bent over to form a jaw or arm H adapted to engage the upper surface of the base of the rail A. In bending the bar to form the jaw D there is formed a surface I adapted to engage the edge of the rail base at the side of the rail B opposite to that en-

gaged by the surface F of the portion E of the rail anchor C.

To place the device in position upon the rail it is first brought to the position indicated by the dotted lines at the right of Figure 3 with the jaw or arm H above the base of the rail A at one side of the rail. The rail anchor C is first moved transversely upon the rail and then longitudinally toward the tie until the tie-engaging portion G contacts with the tie and the jaw or arm D of the rail anchor C begins to engage the top of the rail base at the other side of the rail A from that engaged by the jaw H. The rail anchor C will then be in about the position illustrated by the dotted lines at the middle of Figure 3. When in this position the portion E of the rail anchor C will contact with the bottom of the rail base. Force will be required to get the rail anchor C from the position shown in the dotted lines at the middle of Figure 3. The end of the rail anchor C at which the jaw or arm D is driven toward the rail and away from the tie, so that the jaw D is forced onto the rail base and the rail anchor C moves angularly in relation to the rail with the tie-engaging portion G held to the tie. While the rail anchor C is being thus forcibly moved angularly and transversely with relation to the rail, the portion E rides upon the bottom of the base of the rail A until the surface F will clear the edge of the bottom of the base of the rail C. The elasticity of the rail anchor C then causes the portion E to spring up into the position shown in Figures 1 and 2. The rail anchor C is then in operative position upon the rail with the arms or jaws D and H engaging and pressing down upon the upper surface of the base of the rail A and the surfaces F and I in position to engage opposite edges of the rail base. Contact of the tie-engaging portion G of the rail anchor C with the tie B prevents movement of one end of the rail anchor C further toward the tie.

With the rail anchor C in this position the end of the rail anchor C having the jaw or arm D and the surface I may be driven toward the tie until the surfaces I and F of the rail anchor C engage the edges of the opposite sides of the rail base. The base of the rail A is then firmly gripped by the rail anchor C. The direction in which the rail tends to move or creep is indicated by the arrows in Figures 2 and 3.

The rail anchor is so formed that after it has been placed in operative position upon the rail the grip of the jaw or arm D upon the rail base is such that should the rail move forward in the direction of the arrow it will carry with it the jaw D while the other end of the rail anchor and the jaw or arm H are held by the contact of the tie-engaging portion G with the tie B, so that 10 the angular movement of the rail anchor C produced brings the surfaces I and F into contact with the edges of the rail base and causes the rail anchor C to firmly grip the rail. Any further movement of the rail 15 15 A forward in the direction of the arrows automatically increases the grip of the rail anchor C upon the rail and prevents further forward movement of the rail.

The engagement of the base of the rail A by the rail anchor C in such manner as to effectually prevent loosening or detachment is made sure by the relation of the portion E to the other portions of the rail anchor C and it will readily be seen that, even though 20 movement of the rail in the direction opposite to that in which the rail tends to creep should occur, the position of the surfaces F and I or similar surfaces of the rail anchor C at opposite edges of the rail base will ensure retention of the rail anchor in such position upon the rail base that, so soon as movement in the direction of the arrows is again set up the rail anchor C will again automatically increase its grip upon the rail 25 sufficiently to effectually resist the tendency of the rail to creep.

It will also be readily seen that the rail anchor C may be readily fashioned from a rolled bar by bending or similar simple operations. This permits the use of steel rolled bars of great strength and permits the device to be made much lighter than would be practicable were cast material necessary and 40 at the same time there is the advantage of 45 greater uniformity in strength which rolled steel has as compared with malleable iron or steel castings. Lightness brings also the additional great advantage of lowered cost of transportation.

50 It will be obvious that rolled material of different cross sections might be utilized for the manufacture of the device and that changes in the form, proportion and minor details of construction may be resorted to 55 without departing from the principles or sacrificing any of the advantages of the invention.

I claim:

60 1. A rail anchor, comprising a rolled bar fashioned to provide, at one side of the rail, a portion adapted to embrace the rail base and grip the upper surface and edge thereof; and, at the other side of the rail, a tie engaging portion, an arm adapted to bear upon the upper surface of the rail base and

a seat adapted to engage the edge of the rail base.

2 An anticreeper, comprising a rolled bar bent to form rail base engaging portions upon its two ends adapted to engage and grip the top of the rail base at opposite sides of the rail, a tie engaging portion and a rail base edge engaging seat adapted automatically to engage the edge of the rail base when said anticreeper is forced into position on the rail.

3. A rail anchor, comprising a rolled bar adapted to be applied transversely upon the rail base bent to form at its free end a jaw adapted to grip the top and edge of the rail base and, upon the other end thereof, an arm adapted to engage the top of the rail base, a portion below said arm adapted to engage a tie, and a base edge engaging portion in spaced relation to said arm and tie 30 35 engaging portion.

4. A one piece rail anchor, comprising a bar provided, at one end, with a portion adapted to engage and grip the upper surface of the rail base and, at the other end, with a portion adapted to engage the upper surface of the rail base, a tie abutting portion and a rail base edge engaging seat; the whole adapted to be placed in position upon the rail by forced horizontal angular movement and to be locked in position upon the rail by the engagement of the edge engaging seat with the rail base edge.

5. A rail anchor, comprising a rolled bar, so formed that, when applied to the rail its free end engages and grips the upper surface and edge of the rail base at one side of the rail, an intermediate portion will engage the edge of the rail base opposite said free end, and the other end of said bar so engage the upper surface of the rail base and a tie as to maintain the free end in spaced relation to the tie.

6. A one piece anticreeper, comprising a bent rolled bar having at its ends arms adapted to engage and grip the upper surfaces of the rail base, adjacent the tie at one side of the rail and in spaced relation to the tie at the other side of the rail, a portion adapted to engage a tie, and seats adapted to engage opposite edges of the rail base in spaced relation to the tie.

7. A device for preventing the creeping of rails, comprising a bent rolled bar having at one end an arm adapted to engage and grip the upper surface of the rail base and a seat adapted to engage the edge of the rail base at one side of the rail, in spaced relation to a tie, at the other end, an arm adapted to engage the upper surface of the rail base adjacent the tie, a tie abutting portion and a shoulder adapted to engage the edge of the rail base and lock said device upon the rail.

8. An anticreeper, comprising a rolled bar

bent to form rail base edge engaging seats adapted to engage the two side edges of the rail base in spaced relation to a tie and having one end overturned to form an arm 5 adapted to grip the top of the rail base in spaced relation to the tie, the other end overturned to form an arm adapted to engage the upper surface of the rail base adjacent the tie and a portion adjacent thereto 10 adapted to engage the tie in opposition to the tendency of the rail to creep.

9. An anticreeper, comprising a rolled bar bent to form two seats adapted to engage opposite edges of the rail base, a portion 15 adapted to engage a tie and an arm adapted to engage the upper surface of the rail base in spaced relation to said base edge engaging seats, and an arm adapted to engage and grip the upper surface of the rail base 20 inwardly of one of said base edge engaging seats at the side of the rail away from said tie engaging portion.

10. A rail anchor, comprising a rolled bar having at one end an arm adapted to over- 25 lie and grip the top of the rail base and a seat adapted to engage the edge thereof at one side of the rail and, at the other end, an arm adapted to engage the upper surface 30 of the rail base, at the other side of the rail, a portion adapted to engage a tie, and a seat adapted to engage the edge of the rail base in spaced relation to said tie engaging por- 35

11. A rail stay comprising a rolled bar formed with rail base edge engaging seats, 35 an arm adapted to grip the upper surface of the rail base, at one side of the rail, adjacent one of said seats, an arm adapted to engage the upper surface of the rail base, at the other side of the rail, in spaced relation to said seats and said arm first named, and a portion adapted to engage a tie. 40

12. A one piece rail anchor, comprising a rolled bar having one end overturned to engage the top of the rail base, at one side of the rail, a portion adjacent said arm adapted to engage a tie and a portion adapted to engage the edge of the rail base in spaced relation to said arm and tie engaging portion; and having the other end thereof 50 formed to embrace the rail base and grip the top thereof, at the other side of the rail in spaced relation to the tie.

13. A rail anchor, comprising a rolled bar bent to form arms adapted to grip the upper 55 surfaces of the rail base at opposite sides of the rail, a portion adapted to engage a tie, and a seat adapted to engage the edge of the rail base, all so constructed that, when said arms engage the upper surfaces of the 60 rail base, said seat may be sprung into engagement with the edge of the rail base to lock said rail anchor in operative engagement with the rail.

H. G. GILLMOR.
